FIG. 2

Inventor:
Murray Morrison

UNITED STATES PATENT OFFICE.

MONTFORD MORRISON, OF CHICAGO, ILLINOIS.

METHOD OF AND APPARATUS FOR CONTROLLING ELECTRON DISCHARGE TUBES.

Application filed January 21, 1924. Serial No. 687,516.

The present invention relates to a system of connections and circuits for vacuum tubes of the thermionic-cathode type, such as for example, X-ray tubes and the like.

More specifically, my invention relates to the above class of vacuum-tube devices which operate with the assistance of thermionic cathodes, and has particular reference to such devices when the discharge produced is subject to variations in behavior due to changes in gas ionization within the tube, differences in specific electron emissivity and instability of spontaneous electron liberation.

Among the objects of my invention are; first, to provide a means for stabilizing electron discharge of the apparatus when the source of electrical current for heating the aforesaid thermionic cathodes is subject to variation; second, to provide an improved constancy of conductivity within the tube when the said tube is subject to gas ionization; third, to provide an improved constancy in the electrical conductivity within the tube when the specific emissivity of the incandescent cathodes is subject to variation; fourth, to provide an improved constancy of conductivity within the tube when spontaneous ionization may be present, unstable or subject to variations.

Other and further objects will be pointed out and in part obvious upon reading the specifications and inspecting the drawings, but the novel scope of my invention will be pointed out with certain particularities in the appended claims.

For a thorough understanding of my invention reference may be had to the following description bearing connection with the accompanying drawings in which I have shown three embodiments of my invention in order to illustrate more justly the scope of my claims.

Fig. 1 is an embodiment of my invention showing my controlling apparatus located in the high-tension direct-current circuit of an X-ray-tube system employing a high-voltage rectifier.

Fig. 2 illustrates an embodiment of my invention in the high-tension-alternating-current circuit of an X-ray-tube system employing a high-voltage rectifier.

The art of controlling electron discharge apparatus by mechanical devices subject to discharge current through the tube, is quite old. Such apparatus has been in extensive use in connection with discharge tubes operating with pure gas ionization, and with those in which only non-gas ionization is alleged to occur.

The objects of controllers of the prior art for electron discharge tubes have been particularly directed toward the stabilization of X-ray tubes when the operation is supposed to take place independently of gaseous ionization, and their principal objects have been to provide means for automatically stabilizing the thermionic emission itself without respect to any other phenomena, and have been conceived and constructed with the idea that this one phenomenon was the sole one to be taken into consideration and their operation has been particularly and admittedly called for because of inherent fluctuations in the direct sources of heating current for the thermionic cathodes, as it was believed that these heating-current variations due inherently to line voltage fluctuations were the principal source of operative erraticalness in these tubes.

However, I have discovered that there are four sources of variations in the electrical conductivity of these tubes and that the principal difficulty does not originate from variations in filament excitation voltage but from variation in the aggregate electron emission from the four sources.

The four sources which I have discovered are:

Variations in the temperature of the cathode due to variations in line fluctuations heretofore referred to; variations in the specific electron emissivity of the cathode itself, which may change for many reasons, some of which originate within the cathode filament itself, and some external of it; variations in gas pressure within the tube which not only affect the gaseous ionization but also the electron emission of the filament itself, as well as do they even change the spectrum of the target due to interference with the velocity-distribution of the electron-stream; and also variations in the spon-

taneous ionization of the cathode, which is the pulling out of electrons themselves from various parts of the cathode on which the electro-static stresses are concentrated, due 5 to local impurities, craters, physical-geometrical points, sharp edges and the like.

It will be appreciated by those familiar with the art that it is erroneous to assume that the stabilization of any one of these 10 phenomena will necessarily affect the stabilization of the discharge current as a whole through the tube itself. Further, if the discharge current is to be stabilized as a whole, the aggregate electron liberation 15 must be made constant as a whole, and this may be done by selecting one of the predominating factors of the aforementioned group which may be controlled external of the tube and by constructing device, which 20 will add to or subtract from the value of this selected factor in such a way as to maintain the instantaneous aggregate electron-liberation substantially at a constant value.

25 Means and method, for doing this directly by electrical circuit systems without the interposition of translating devices subject to operation by currents involved, are the substance of this invention.

30 In most of the controlling devices of the prior art some sort of relay, subject to operation by means of the discharge current through the tube has been used to accomplish their result. In the first case on record 35 a simple relay resembling a d'Arsonval meter-element, was used, in which the armature was actuated by the discharge current through the tube and made to operate an osmosis regulator which might raise or 40 lower the conductivity of the tube. In any such mechanical device constituting a means subject to operation by the discharge current, there resides many inherent disadvantages and difficulties due to failure of the 45 various mechanical parts involved to function repeatedly and continuously, identically.

50 In further development of the relay element above described, instead of being actuated by intermittent current, it was made to vibrate synchronously with the alternations of a line voltage, and this vibrating action in conjunction with contact-points and the like, have been utilized to accomplish the stabilization of discharge current during the process of pumping radio-telegraphic and radio-telephonic thermionic vacuum-tubes, and later X-ray tubes and the like.

55 It will be appreciated by those familiar with the art that in such vibrating systems where the amplitude of vibration is only of the magnitude of .0015 inch, that small differences in temperature causing the 60 expansion of parts thereof, may totally dis-

able the device. Further, that since these contacts necessarily operate under currents of several amperes, that the local welding of the said contacts is likely to occur and thus disable the device. Further, that with such 70 small clearances between the contacts, dust, condensed moisture, and the like, are very apt to seriously interfere with the proper functioning of the stabilization as a whole. Again, these relays not only vibrate within 75 the contacts themselves but inherently within the trunnions due to the inherent mechanics of the system and thus rapidly wear themselves out of adjustment. The performances imposed upon this instrument and 80 the limits of variation in its behavior result in its being almost impractical as an operative device and its use in the art for this reason has been largely abandoned.

85 In the present invention, I eliminate all vibrating and relay parts such as used in the case of the vibrating relay, which is supposed to operate synchronously with the line voltage; and further, I eliminate all discharge-current mechanically-operated devices, and all means subject to or responsive to any electrical condition of the current in said tube for regulating electron emissivity of the cathode, and as contrasted 90 with which aforesaid devices I employ the electron discharge-current itself, or a different current proportional thereto, to affect the desired characteristics of the stabilization of the aggregate electron libera- 95 tion.

100 By such method and means as constitute my invention I eliminate and obviate the use of all uncertain vibrating parts of the prior-art mechanical-devices and therefore produce a system which is a considerable 105 advance over the said art.

Referring to Fig. 1, 1 is a source of alternating potential which by means of leads 2 and 3, supply primary 4 of step-up transformer 5 with electrical energy. Primary 110 circuit of said transformer 5 may be supplied with a switch 6 for practical purposes, and the primary of which transformer may be supplied with means 7 for adjusting the magnetic induction in the core of the said 115 transformer in order to produce different voltages in the secondary 8 thereof. Leads 9 and 10 conduct current to the alternating current terminals 11 and 12 of a rectifier 13, which is preferably of a form fully set forth in my United States Letters Patent 120 No. 1,466,541, issued August 28, 1923. 14 and 15 are the direct current terminals of said rectifier. Lead 16 conducts positive 125 electricity to the anode terminal 17 of an X-ray tube 18, preferably enclosed within a shield 19, as set forth in my application Serial Number 633,712, filed April 21, 1923.

130 Lead 20 conducts negative current to my stabilizing apparatus, which current is

thence conducted to the cathode 47 of X-ray tube 18. X-ray tube 18 may be supplied with a current-measuring device A for practical purposes. Alternating potential source 1, through leads 21 and 22, supply transformer 23 with energy, the circuit of which may have a switch 24 for practical purposes. The secondary 25 of transformer 23 is supplied with the voltage adjustment 26, and the circuit of which may contain an adjustable resistance 27, in series with an adjustable inductance 28, in series with an adjustable capacity 29.

These three circuit elements and the source of variable potential are all in series with a primary 30 of an insulation transformer 31.

It will be appreciated by those skilled in the art that with a source of adjustable voltage in series with adjustable resistance, adjustable inductance and adjustable capacity, that the voltage impressed upon 30 may have any root-mean-square value and phase angle with reference to alternating potential source 1, that may be desired, or requisite for the operation of my device. Brackets 32 are used as being symbolic of possible simultaneous adjustment of the four adjustable factors enclosed by them. Insulation transformer 31 supplies electrical energy for the several elements of my system of circuits and simultaneously electrical insulation between high voltage lead 20 and source of electrical potential 1.

Rectifier 13 is driven synchronously with alternating potential source 1, either by direct mechanical connection or by means of synchronous motor drive. Such connection between these elements is omitted for the sake of clearness, as this is not a novel element of my invention and is well understood by those familiar with the art.

Insulation transformer 31 has its secondary 33 connected to leads 34, which supply exciting current for the stator of the synchronous motor 35, driving a commutator 36. The armature and several mechanical parts of the said synchronous motor is not brought into view for the sake of clearness. Secondary leads 34, also supply filament 47 of X-ray tube 18 with electrical heating energy through concentric conductors 36. The circuit from the secondary 33 which supplies the aforesaid heating current to the filament 47, has connected in series with it the primary 37 of a current transformer 38, and the said concentric leads 36 have shunted across them an inductive resistance 39 at the middle point of which is connected a lead 40, which supplies conductivity to brush 41 of commutator 36. The two half elements of said resistance, formed by connecting lead 40 to resistor 39, are shunted by condensers 42 and 43.

Lead 20 is conducted to brush 44 of commutator 36 through two equal inductances 45 and 46. Commutator 36 is shunted by condenser 48; inductance 46 and commutator 36, are jointly shunted by condenser 49. Inductances 45 and 46, and condensers 48 and 49, form a filter circuit which may be adjusted to selectively filter out, of the circuit including the commutator 36, such higher harmonic components of the X-ray tube current as may be desirable or advantageous.

The function of the middle connection to resistor 39 is to allow the negative current arriving from lead 20 to divide equally between the two concentric conductors 36, which in conjunction with the shunt condensers 42 and 43 provides a balance of conditions between the filament heating current circuit and the discharge current circuit of the X-ray tube, such that difficulties from high frequency phenomena are minimized.

Current transformer 38 is provided with a secondary 50, across which is shunted brushes 51 and 52 of commutator 36. The operation of this apparatus is as follows:

Source of alternating current 1 is made to function; switch 24 is closed. Transformer 23 is supplied with electrical energy and insulation transformer 31 is in turn supplied with such voltage at such phase angle, by means of adjustment of voltage 25, resistance at 27, inductance at 28 and capacity at 29, as will give the desired phase relation between the current in the primary 37 of current transformer 38, and that of its secondary 50, as will be more fully hereinafter appreciated.

Transformer 31 receiving energy, imparts excitation to stator 35, which starts and operates commutator 36 synchronously with alternating current source 1, and with the proper phase relation and polarity with respect to the currents involved in its functioning. Further, current from secondary 33 flows through primary 37 to filament 47, giving the said filament the proper excitation to emit the desired number of electrons.

The reactance of transformer 38 has the effect of giving a slight different excitation to filament 47 in the absence of current through secondary 50, but this is not materially undesirable or detrimental to the operation of my device. Under the condition of operation, so far explained, resistor 39 and condensers 42 and 43 take a small amount of current from secondary 33, but this plays no essential rôle in the operation of the apparatus.

Rectifier 13 being connected mechanically or synchronously to alternating current source 1, is in proper rotation, phase angle and polarity, simultaneously with the proper functioning of alternating current source 1,

so that switch 6 may be now closed, adjustment 7 manipulated so that secondary 8 of transformer 5 has its proper operating voltage, upon which status of affairs X-ray tube 18 is supplied with main electrode-discharge current.

The current from lead 20, being conducted to brush 44, is directed through secondary 50 before it arrives at brush 41, after which it is directed to cathode 47 through condensers 42 and 43 and resistor 39. Resistor 39 is illustrated as being wound inductively, as in the operation of this inductive resistance, in conjunction with the shunted condensers, the inductive effect in the said inductive resistance is not apparent in the average current passed under the conditions set forth in this case, namely; that of the passage of unidirectional current.

The function of the commutator 36, is to redirect the pulsating rectified currents of the main electrodes of the X-ray tube 18 so that they re-form an alternating current, in secondary 50 which was their original form in secondary 8.

The utilization of this discharge current in its alternating form instead of its direct current form is for the purpose of combining it inductively in secondary 50 with the sinusoidal current in primary 37, as will now be explained. The current through primary 37, is of the common sinusoidal form. The current in 50 is of the magnitude of a few milliamperes, and the current of primary 37 is of the magnitude of several amperes. The current transformer 38 and its ratio of transformation is called for and fixed such that the effects of these two currents on the magnetic induction on the core of transformer 38 are comparable in magnitude and hence these two currents may be made to combine in effect much as if they were of the same order of current themselves.

The combined effect of these two currents under the condition specified is such that the filament excitation current assumes a compromised form and it will be appreciated that the greater the discharge current through the tube the greater amplitude is given to curve the current in a secondary 50, hence the greater amount is subtracted from the heating current in primary 37, leaving less of it for filament excitation, which means lower thermionic discharge currents through the tube.

It will be appreciated by those familiar with the art relating to discharge tubes that the thermionic discharge current is not directly proportional to the filament excitation current, but after the excitation current has risen considerably the thermionic current rises much more rapidly, and hence at

high filament excitation currents the thermionic discharge current is very sensitive to small differences in the said excitation current. This means, with relatively small amounts of current taken from or added to the heating current, after it has been allowed to rise to a considerable value, that in the present invention the thermionic discharge current can be made to vary considerable even by small differences of discharged current. This means that if any one of the aforementioned variations in conductivity of the X-ray tube comes into play, the slight increase or decrease in the said conductivity tends to produce a large difference in thermionic emission, thus giving a very sensitive stabilizing effect to the conductivity of the X-ray tube.

In Fig. 2 is shown a system of connections attaining the same ultimate results as the system in Fig. 1, the only difference being that in Fig. 1 the control system is in the high-voltage pulsating-current circuit of the X-ray tube and, therefore, the commutator is required to turn the main electrode discharge current back into alternating current, in order that it may operate in proper combination with the alternating exciting current of the X-ray tube filament.

In Fig. 2 the control system is located in a certain alternating-current portion of the high-voltage circuit, which portion is so insulated that it may be grounded and the controlling-system commutator is not required. Otherwise the operation is substantially the same.

In Fig. 2, all parts common to both figures have been given similar numerals, and this includes all numerals from 1 to 34 inclusive, and 45 to 49 inclusive, and with this understanding the repetition of the identical descriptive matter is eliminated.

It will be appreciated that the main electrode current of the X-ray tube 18, as it flows through secondary 8, is alternating in character, as it has not been commutated by rectifier 13 at this time. Inductances 45 and 46, and condensers 48 and 49 will be observed to constitute the same filter as indicated by these numerals in Fig. 1.

Secondary 8 has the center of its winding connected to this filter and shunted by a three-electrode air gap 53, one electrode of which is connected to the center of the high-turn winding 50 of the current transformer 38, which is common to both figures, and said transformer is supplied with a high-frequency and static-potential-shield 54, common in transformer art, which shield is grounded. In addition, the high-voltage filter-circuit is supplied with resistors 55 and 56, which over and above the action of the filter proper not only assists in spark-over at gap 53 in the case of surges, and the like;

but also limits the short circuit current in this filter circuit during spark-over when energy is being transmitted to the said circuit through primary 37, which is the case 5 under operating conditions.

It will be appreciated by those skilled in the art that with only the consideration of such parts of Fig. 2 as have been described by similarity to Fig. 1, and explicitly under 10 the description of Fig. 2 so far, that the operation of this set-up is substantially the same as that of Fig. 1.

As appreciated by those skilled in the art, the current in primary 4 of transformer 5 is 15 very similar and closely proportioned to the current in secondary 8 of the said transformer, when the exciting current component of the transformer supply current does not form a substantial factor in the total primary current. Therefore in some cases I 20 may desire to close the switch 57, open the switch 58, and open switch 59, which throws into circuit in place of transformer 38, a transformer 60 having a winding 61 similar 25 to that of 38 indicated by numeral 37, and a low-turn winding 62 which is called for to be different than 50 by reason of the ratio of transformation in transformer 5. It 30 will be observed that this is merely a transfer of stabilizing circuits from the secondary of the high-voltage transformer to the primary circuit, and the theory of operation is substantially the same as that already described, in the case of a low exciting current 35 transformer being used at 5.

It will be appreciated by those skilled in the art that the invention described and the embodiments illustrated, comprise a system of control which has no parts nor means 40 responsive to electrical conditions of current transmitted by the tube for stabilizing the tube operation, but all such parts and means have been eliminated; and the stabilization of the tube conductivity, with particular 45 consideration of the aggregate electron liberation, is caused by the electrical condition of the current itself without other means.

What I claim is:—

1. The combination of a thermionic X-ray 50 tube having conductivity subject to variations in the temperature of its cathode, variations in the specific emissivity of said cathode, variations in the gas pressure within the envelope of said cathode, variations 55 in the spontaneous liberation at said cathode, a high voltage rectifier for commutating voltage for the X-ray tube main-electrodes, an independent source of alternating heating-current for the cathode of said tube, and means for converting the rectified tube current, in an auxiliary circuit associated with the said heating current back into alternating current, whereby the interaction between the said heating current and the said 60 converted tube current causes said tube to

operate according to a desired characteristic.

2. The combination of a thermionic X-ray tube having conductivity subject to variations in the temperature of its cathode, variations in the specific emissivity of said 70 cathode, variations in the gas pressure within the envelope of said cathode, variations in the spontaneous liberation at said cathode, a high voltage rectifier for commutating voltage for the X-ray tube main-electrodes, an independent source of alternating heating-current for the cathode of the said tube, and means for associating the current of the main-electrodes in alternating current form with the heating 75 current of the said electrode, whereby the interaction between said heating current and the said current of the main electrodes in the said form causes the tube to operate according to the desired characteristic. 80

3. The combination of a thermionic X-ray tube having conductivity subject to variations in the temperature of its cathode, variations in the specific emissivity of said 90 cathode, variations in the gas pressure within the envelope of said cathode, variations in the spontaneous liberation at said cathode, a high voltage rectifier for commutating voltage for the X-ray tube main-electrodes, 95 an independent source of alternating heating-current for the cathode of the said tube, means for associating the current of the main-electrodes with the heating current of the said cathode, and means for adjusting the phase relation between the current of the main-electrodes and the said heating current, whereby the conductivity of the tube is caused to assume the desired characteristic. 100

4. The combination of a thermionic X-ray tube having conductivity subject to variations in the temperature of its cathode, variations in the specific emissivity of said cathode, variations in the gas pressure within the envelope of said cathode, a source of high potential current for the X-ray tube main-electrodes, an independent source of alternating heating-current for the cathode of the said tube, means for associating the current of the main-electrodes with the heating current of the said cathode, and means for adjusting the phase relation between the current of the main-electrodes and the said heating current, whereby the conductivity 110 of the tube is caused to assume the desired characteristic. 115

5. The combination of a thermionic X-ray tube having conductivity subject to variations in the temperature of its cathode, variations in the specific emissivity of said cathode, variations in the gas pressure within the envelope of said cathode, variations in the spontaneous liberation at said cathode, a high voltage rectifier for commutating 120 125 voltage for the X-ray tube main-electrodes, an independent source of alternating heating-current for the cathode of the said tube, and means for associating the current of the main-electrodes with the heating current of the said cathode, 130

voltage for the X-ray tube main electrodes, whereby the range of stable main-electrode current may be fixed to a desired mean-value.

means for associating the current of the main electrodes with the heating current of the said cathode, and means for adjusting the specific value of the said association,

10

In witness whereof, I have hereunto set my hand this seventeenth day of January, 1924.

MONTFORD MORRISON.
